[57] CLAIM

The ornamental design for a flashlight, as shown and described.

DESCRIPTION

FIG. 1 is a side elevational view of the left side of a flashlight showing my new design, with a movable stand being in a flush position against the flashlight body, the right side being a mirror image thereof;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view of the left side of the flashlight embodying my new design, showing the movable stand being in an open position such that the flashlight is supported and angled, the right side being a mirror image thereof; and,

FIG. 7 is an exploded perspective view of the flashlight embodying my new design, in which an end cap screwably-received in the flashlight body has been removed, the end cap being dimensioned so as to form a storage compartment when joined to the flashlight body.
